(57) **CLAIM**

The ornamental design for a ring, as shown and described.

DESCRIPTION

FIG. 1 is a front view of the ring;
FIG. 2 is a left view of the ring of FIG. 1, the right side view
being a mirror image thereof;
FIG. 3 is a perspective view of the ring of FIG. 1;
FIG. 4 is a top view of the ring of FIG. 1,
FIG. 5 is a bottom view of the ring of FIG. 1; and,
FIG. 6 is a rear view of the ring of FIG. 1.

The ring is typically used as a piece of jewelry, and is placed
on the fingers of individuals primarily for decorative purposes.
The ring is comprised of a hollow circular body with
a jewel centerpiece set on the ring.
